UNITED STATES PATENT OFFICE.

WILLIAM R. McLAIN, OF CHICAGO, ILLINOIS, ASSIGNOR OF ONE-HALF TO
THOMAS E. O'BRIEN, OF SAME PLACE.

REVERSIBLE RAIL FOR BEDSTEADS.

SPECIFICATION forming part of Letters Patent No. 653,753, dated July 17, 1900.

Application filed February 19, 1900. Serial No. 5,751. (No model.)

To all whom it may concern:

Be it known that I, WILLIAM R. McLAIN, of Chicago, in the State of Illinois, have invented certain new and useful Improvements 5 in Reversible Rails for Bedsteads, of which the following is a specification.

This invention relates to bedsteads in which rabbeted or L-iron side rails are used to support and hold the bed-bottom in place. The 10 bottoms for this class of bedsteads are provided in some instances with a straight edge adapted to fit within the angle of the side rails and in other instances with a rabbet adapted to fit over or outside the angle of the 15 rails. As a consequence, it is desirable to have the rails reversible in the bedstead, so as to present either the inside or the outside of the L-iron upward to receive the bed-bottom; and the object of my improvements is 20 to provide means for a conveniently detachable and reversible connection for the side rails in the bedstead. I attain this object by the means illustrated in the accompanying drawings, in which—

25 Figure 1 is a perspective view of the side rail of a bedstead of the class mentioned provided with my improvements. Fig. 2 is an end view of the rail. Fig. 3 is a section on the line 3 3 of Fig. 2. Fig. 4 is a horizontal 30 section on the line 4 4 of Fig. 2, extended to include a fragment of the bedstead at the end of the rail and show the relation and connection of the rails therewith. Figs. 5 and 6 are details showing detached parts in perspective.

35 In the drawings, A designates an L-iron side rail provided with metallic end pieces A', which have square end faces provided with detachable and reversible dovetail connecting-pieces a of conical form. These are 40 adapted to fit corresponding sockets a' in the headpiece and the footpiece B of the bedstead for connecting the rails therewith. The dovetail connecting-pieces have an integral base portion C, which is fitted into a corresponding groove or recess C' C' in the square 45 end faces of the rail for holding the connecting-pieces securely against displacement on the rails by torsional strain. In the bottom of the recess a threaded nut D is secured, or 50 a suitable threaded hole d d is provided in the end of the rail, so that a screw or bolt E,

passing through an unthreaded hole e e in the connecting-piece and its integral base, will engage with the rail and securely hold the connecting-piece in connection therewith 55 and its base within the recess. The auxiliary effect of the base within the recess in preventing torsional displacement by twisting strain on the rails enables a single bolt to serve where otherwise at least two bolts would 60 be required, and proportionately reduces the labor required to reverse the rails. The hole e e is counterbored in the dovetail part to receive the slotted head e' of the bolt, the outer end e'' of which is shaped and adapted to fall 65 in line with the conical surface of the connecting-piece at one or more points when the head is fitted to the bottom of the counterbore, so that the outer end of the head will have bearing against the wall of the socket a' when the 70 connecting-piece is fitted therein. This bearing of the socket upon the outer end of the bolt operates as a lock upon the bolt to prevent its connection with the rail from becoming loose or shaky when the rail is connected 75 to the headpiece and footpiece of the bedstead. The part C is reversible in the groove or recess C' C', the hole e e therein being adapted to register alike with the hole d d in the rail in either position of the part C, so 80 that the taper of the conical connecting-piece can be put in reverse positions with relation to the angle of the rail, and in either will fit alike in the socket a' of the head or foot piece of the bedstead. The head of the bolt E being 85 provided with a slot or groove, an ordinary screw-driver may be used to disconnect and reconnect the connecting-piece when the rail is removed from the bedstead to reverse the rail and make it fit with either of the two 90 styles of bed-bottom mentioned.

What I claim is—

1. The combination with the side rail of a bedstead provided with square end faces and a threaded hole in each end face of reversible dovetail connecting-pieces provided with a bolt-hole, said connecting-pieces respectively abutting upon the square end faces of the rail, one of the abutting surfaces being provided with a recess and the other with a 100 companion piece entering the recess, and a screw-bolt for each connecting-piece adapted

to pass through the bolt-hole therein and engage the threaded hole in the end of the rail as specified.

2. The side rail of a bedstead provided with 5 a recess in each of its end faces and a threaded hole in the bottom of the recess, in combination with dovetail connecting-pieces, provided with a base portion adapted to fit the recess in reversed positions, and an unthreaded hole through the dovetail and base por-

tions and counterbore in the dovetail part, and a screw-bolt having a slotted head adapted to fit the counterbore and a point adapted to engage the threaded hole in the rail as specified.

WILLIAM R. McLAIN.
